UNITED STATES PATENT OFFICE.

EMIL GATHMANN, OF BALTIMORE, MARYLAND.

INGOT MOLD.

Application filed October 3, 1925. Serial No. 60,260.

To all whom it may concern:

Be it known that I, EMIL GATHMANN, a citizen of the United States, and resident of Baltimore, in the State of Maryland, have invented certain new and useful Improvements in Ingot Molds, of which the following is a specification.

This invention relates to ingot molds of the kind in which the mold chamber has a bottom opening closed by a plug while casting, and which is stripped or has the ingot removed from the mold by forcing the plug into the mold cavity so as to raise the ingot to a sufficient extent to permit it to be engaged by lifting devices which withdraw it from the mold.

My invention consists in giving a novel shape to the lower portion of the mold cavity whereby the escape of molten metal from the bottom of the mold is prevented and the lodgement of foreign matter on the lower walls of the mold cavity is avoided.

My invention is preferably applied to a mold of the big-end up type. Such molds are generally used in connection with feeders or shrink head casings made of refractory or semi-refractory material which have a tendency in molds as previously constructed, to drop lumps or particles into the mold which tend to lodge on the side walls of the lower portion of the mold chamber when the ingot is stripped from the mold. This has sometimes been a serious matter, but it is remedied by my invention.

By my invention also the mold chamber is so shaped that the ingot formed therein will be free from fish tails or thin flanges which would interfere with the proper rolling or working of the ingot.

My improvements are illustrated in the accompanying drawings, in which:

Figure 1 is a vertical central section of an ingot mold embodying my improvements, showing the mold resting on a stool or support of ordinary construction.

The remaining figures are on an enlarged scale.

Figure 2 is a plan view of the mold.

Figure 3 shows a vertical section through the lower portion of the mold on the line 3—3 of Figure 2.

Figure 4 shows a vertical section of the lower portion of the mold through the

corners thereof on the line 4—4 of Figure 2.

A big-end up ingot mold A of the Gathmann type is shown in Figure 1, although my invention may be applied to molds of other kinds. The mold cavity B is wider at top than at bottom and it is provided with a bottom opening C preferably formed with downwardly tapering walls as shown. The mold rests on a stool or support D, having an opening d directly under but preferably somewhat wider than the opening C. While casting, the bottom opening of the mold is closed by a plug E, the upper portion of which fits the walls of the opening C and the lower portion of which extends into the opening in the stool.

In common practice, after the ingot is cast, the plug E is raised by suitable apparatus so as to lift the ingot in the mold to a sufficient extent to permit lifting tongs or other suitable devices to engage the upper end of the ingot and withdraw it from the mold, thus making it unnecessary to move the mold from its support during the stripping operation.

My United States Patent No. 1,188,751 of June 27, 1916 shows a mold of somewhat similar construction to that shown in the accompanying drawings, in which the lower part of the mold cavity is necked in, being formed with concave walls which extend from the major mold walls inwardly and downwardly toward the bottom opening of the mold, but which join and merge into convex wall portions which in turn merge into the side walls of the bottom opening of the mold. These convex or curved walls as shown in my prior patent, are of much smaller radius than that of the concave walls. I have found that improved results are obtained by making the bottom opening of the mold wider than heretofore, and by giving to the major convex walls substantially the same radius as the concave walls. In this way I avoid the formation of a ledge or ledges which would tend to catch and hold foreign matter, such as lumps or particles of the shrink head casing which might be detached and dropped into the mold during the stripping operation. Such foreign matter in the mold would seriously interfere with the subsequent use of the mold.

The necked in portion of the lower part

of the mold surrounding the bottom opening thereof should be of such angular contour that any particles dropping into the mold will automatically slide down into and through the bottom opening when it is not closed by a plug or other closure.

As shown in the accompanying drawings, the major walls of the mold cavity are tapered downwardly and they merge into concave walls α which in turn merge into convex walls α' . Broadly speaking, this arrangement is similar to that in my before mentioned patent, but I have found that decided advantages are obtained by forming 15 the convex walls of the sides of the mold of substantially the same radius as the concave walls, thus avoiding the formation of ledges which would tend to catch and hold foreign matter and thus facilitate the sliding downwardly through the bottom opening of the mold of any foreign matter which may be deposited in the mold.

By way of example I have shown in Figure 3 concave and convex walls formed with 25 a three inch radius. Figure 2 indicates that the corners of the mold cavity are given a differential shape and in view of this difference in the shape of the mold cavity at the corners, it is desirable to form the concave walls at the corners with a five inch 30 radius and the convex walls with a three inch radius.

The drawings indicate the preferred radii and also the preferred dimensions of different parts of the mold. These dimensions 35 are not binding but are relative.

By the construction shown following the general relative dimensions indicating sticking of the ingot in the mold at its lower 40 end and all leakage of the molten metal beneath the outer mold walls is entirely prevented.

The dimensions indicated on the drawings as before stated are by way of example and 45 are relative. As shown the ratio of the opening in the bottom of the mold is substantially seven to nine, i. e. when the bottom opening has a maximum cross section of seven inches, the cross section of the mold 50 chamber where the necking in begins is nine inches. In molds of larger size, the relative cross section should be fourteen inches to eighteen inches; twenty-eight inches to thirty-six inches; and so on.

55 By using a large bottom opening and a large plug or closure a greater chilling surface is provided and a large target is afforded for the pouring operation, thus avoiding to a great extent the impact of the molten metal against the side walls of the mold cavity which would tend to cut said walls or weld some of the molten metal to them and thus make it difficult to withdraw the ingot from the mold.

60 65 I claim as my invention:

1. A metallic ingot mold having an opening through its top and through its lower end and having a vertically extending ingot-forming chamber, the lower side walls of which above the bottom opening have concaved necked-in portions that join side walls of convex contour which are interposed between the walls of the bottom opening and the said concave walls, the corners of the mold in its lower portion being 70 necked-in and concaved with a larger radius than that of the concaved side walls.

2. A metallic ingot mold having an opening through its lower end and having a vertically extending ingot forming chamber, 80 the lower portion of which above the bottom opening is formed with major concave necked-in walls which join major convex walls interposed between the side walls of the bottom opening and said major concave 85 walls; the corners of the mold in its lower portion being necked-in and concaved with a larger radius than said concave major walls.

3. An ingot mold having an opening 90 through its lower end and having a vertically extending ingot forming chamber, the lower portion of which above the bottom opening is formed with major concave necked-in walls which join major convex 95 walls of substantially the same radius which are interposed between the side walls of the bottom opening and the said major concave walls, the corners of the mold in its lower portion consisting of secondary concave walls which are necked-in and concaved with a larger radius than that of said concaved major walls.

4. An ingot mold having a wide, round, 100 tapered opening through its lower end and a vertically extending ingot chamber the lower portion of which above the bottom opening is formed of convex and four major concave walls which join the convex walls, the corners of said mold in its lower portion having four concave secondary walls, the radius of which is larger than that of the concave major walls.

5. An ingot mold having a round, inwardly tapered opening at its lower end and having an ingot forming chamber, the lower portion of which, that merges into the bottom opening, is formed of convex walls and with concaved walls which merge into the convex walls, the corners of the mold in its lower portion being necked-in and concaved with a larger radius than that of the said previously mentioned concave walls.

6. An ingot mold having a round, inwardly tapered opening through its lower end and having a vertically extending ingot forming chamber, the lower portion of which above the bottom opening is shaped to merge into convex walls which in turn merge into upwardly extending concave 130

major walls and into concave corner walls, which are likewise formed with a concave contour, the radii of the concave corner ¹⁰ walls being greater than the radii which form the concave contour of the major walls.

- 5 7. A metallic ingot mold having a vertically extending ingot chamber, the lower major walls of which are formed of a concave contour and the lower corner walls of

In testimony whereof, I have hereunto subscribed my name.

EMIL GATHMANN.
